MARCUS C. HINCKLEY, OF TRUMBULL, CONNECTICUT, ASSIGNOR TO COLUMBIA PHONOGRAPH COMPANY, INC., OF BRIDGEPORT, CONNECTICUT, A CORPORATION OF NEW YORK

DESIGN FOR A RADIOCABINET

Application filed February 18, 1933. Serial No. 47,255. Term of patent 7 years.

To all whom it may concern:

Be it known that I, MARCUS C. HINCKLEY, a citizen of the United States, residing in Trumbull, in the county of Fairfield and State of Connecticut, have invented a new, original, and ornamental Design for Radiocabinet, of which the following is a specification, reference being had to the accom-

panying drawing, forming a part thereof.

Fig. 1 is a front elevational view of the new cabinet; and

Fig. 2 is a top plan view thereof.

I claim:

The ornamental design for a radiocabinet substantially as shown.

MARCUS C. HINCKLEY.
